ROTARY KILN

George Frederick Horton, Houston, Tex.

Application June 24, 1935, Serial No. 28,179

6 Claims. (Cl. 263—22)

This invention relates to improvements in rotary kilns for burning or drying materials of all kinds, especially those materials that require mixing or stirring in a constant heat, and is particularly useful for burning lime from oyster shells.

The primary object of the present invention is to provide a simple and efficient rotary kiln by means of which a desired material may be properly and economically burned or dried in batches of the desired quantity or size.

A more specific object of the present invention is to provide a rotary kiln of the above kind in which the material to be burned or dried is subjected to the action of hot gases or products of combustion flowing into and out of the kiln, and wherein discharge of the gases or products of combustion from the kiln is conveniently controlled for keeping the temperature within the kiln at a proper and constant degree so that a superior product results from use of the kiln.

A further object of the present invention is to provide a kiln of the above kind including a drum having means for rotating the same in one direction to constantly mix or stir the material being burned or dried, and having means for rotating the same in an opposite direction and for automatically discharging the material from the drum when rotated in such opposite direction.

Other objects and features of the invention will become apparent from the following description when considered in connection with the accompanying drawings, in which:

Figure 1 is an elevational view, partly broken away and in section, of a rotary kiln embodying the present invention.

Figure 2 is a top plan view thereof.

Figure 3 is a longitudinal section on line 3—3 of Figure 2.

Figure 4 is a vertical transverse section on line 4—4 of Figure 3; and

Figure 5 is an elevational view showing a modified form of drum which may be employed in lieu of the drum of the kiln shown in Figures 1 to 4 inclusive.

Referring more in detail to the drawings, the present kiln includes a rotary drum consisting of a cylindrical body 5 having conical ends 6 and 7. This drum is mounted to revolve about a horizontal axis, and for this purpose, the end 6 is journaled on a stationary hollow shaft 8 secured to the upper end of a vertical standard or upright 9, and the end 7 has a concentric external circular track 10 resting upon spaced idlers 11 and

11a, respectively shown in Figures 1 and 3, and carried by a suitable support 12.

The stationary hollow shaft 8 projects into the end 6 of the drum and forms a conduit for supplying hot gases or products of combustion to the interior of the drum. For this purpose, the shaft 8 may be connected with the combustion chamber of a suitable furnace to receive the hot gases or products of combustion therefrom. The hot gases or products of combustion are allowed to discharge from the opposite end 7 of the drum through an axial discharge pipe 13 whose inner end is secured to and supported by a spider 14 rigidly mounted in the end 7 of the drum. The end 7 of the drum has a relatively large axial opening at the apex thereof, and the discharge pipe 13 projects outwardly through this opening centrally of the latter and in spaced relation to the wall of such opening as shown clearly in Figure 3. Adjustably threaded on the projecting outer end of pipe 13 is a closure disk 15 having an operating hand wheel 16 and adapted, when threaded toward the end 7 of the drum to close the opening in such end as shown by full lines in the several views. On the other hand, when the closure disk 15 is threaded away from the end 7 of the drum, the opening in this end of the drum will be opened to permit discharge of material from the drum. The pipe 13 is preferably connected with a conduit 17 for conducting the hot gases or products of combustion from the kiln and discharging them at a suitable distant point. In order to permit rotation of the pipe 13 and closure disk 15 with the drum, the outer end of pipe 13 is preferably connected with conduit 17 by means of a swivel connection 18. In the conduit 17 is provided a suitable shut-off valve 19 whereby the discharge of hot gases or products of combustion from the kiln may be readily controlled to maintain the temperature in the kiln at a proper and constant degree.

The cylindrical body portion 5 of the drum is provided with a suitable opening having a closure 20 provided with suitable means generally indicated at 21 for releasably holding the same securely closed. Obviously, the closure 20 may be opened for permitting introduction of the material to be burned or dried into the kiln when the latter is brought to a standstill with the charging opening located at the top as shown in the several views.

Power operated means is provided for rotating the drum in opposite directions, and for this purpose the drum may have an external ring gear 22 near the end 6 meshing with a pinion 23 carried

by a driven shaft 24, the shaft 24 being operatively connected with a suitable motor 25 through a conventional reversing gearing 26 and meshing gears at 27. By proper manipulation of the reversing gearing 26, the drum may be driven in one direction for mixing or stirring the material therein, or the drum may be driven in an opposite direction, at will. Means is provided for automatically discharging the burned or dried material from the kiln when the latter is rotated in such opposite direction and the closure disk 15 is opened. Such means preferably consists in spiral scoop-like blades 28 on the interior of the body portion 5 and the end 7 of the drum and terminating at 5 the discharge opening in said end 7 as shown clearly in Figure 3. Obviously, due to the spiral and scoop-like form of the blades 28, they will scoop up the material and convey it toward the discharge opening in the end 7 when the drum 10 is rotated in one direction, and due to the conical form of the end 7, the blades 28 converge at this end and provide for travel toward the discharge opening through the action of gravity as well as due to the feeding action of the spiral blades. On 15 the other hand, driving of the drum in the reverse direction will result in merely mixing or stirring the contents of the drum, the blades 28 keeping the material or contents in the body portion 5 and end 6 or away from the discharge 20 opening and the end 7 in which said discharge opening is provided.

As shown in Figure 5, the drum may be formed in two longitudinal sections consisting of a large main section 29 and a smaller section 30 detachably joined or bolted together as at 31. In such case, the charging opening and its closure will be unnecessary, the section 30 of the drum being removable for charging purposes. With such construction, the driving mechanism may be operatively connected with the drum by providing the latter with a gear 22a at the small end of the end portion 6 of the drum, the shaft 24 being suitably geared and operatively connected with this gear 22a. Otherwise, the construction of the drum shown in Figure 5 will correspond to that of the drum shown in the other views and like parts are indicated by similar reference characters in all of the views.

It is to be particularly understood that the driving mechanism may be varied greatly, and the driving mechanism illustrated is simply shown by way of example.

It will be noted that the present invention differs materially from the common rotary kiln in that it is not adapted for continuous burning or drying, but is used for burning or drying material in successive batches of a desired size, one at a time. Also, with the use of the present invention, the material to be burned or dried is readily subjected to a fixed heat for a definite time, the temperature being controlled by controlling the discharge of hot gases or products of combustion from the kiln. A particular feature of the invention is that it is not necessary to permit any flame to enter the drum or to get the heat by using fire on the outside of the drum, for the reason that, when desirable, the heat may be furnished by hot gases which are generated in a furnace separate from the drum and conducted to the latter. On the other hand, when desirable, as in the case of drying materials which will not be injured by extensive heat or by the effect of a direct flame, the heat may be generated within the drum itself by electricity and/or other heat producing means.

From the foregoing description, it is believed that the construction and operation, as well as the advantages of the present invention, will be readily understood and appreciated by those skilled in the art. Minor changes in the details 5 of construction illustrated and described are contemplated within the spirit and scope of the invention as claimed.

What I claim as new is:

1. A rotary kiln of the character described comprising a drum mounted for rotation about a horizontal axis and having a conical end provided with an axial material discharge opening, a pipe projecting axially through said conical end of the drum in spaced relation to the wall of said 15 material discharge opening for conducting hot gases and products of combustion from the drum, a manually openable closure for said material discharge opening, and a stationary hollow shaft upon which the other end of said drum is journaled, said last-named shaft being adapted for connection with a source of hot gases or products of combustion whereby the latter are introduced into said drum. 20

2. A rotary kiln of the character described comprising a drum mounted for rotation about a horizontal axis and having a conical end provided with an axial material discharge opening, a discharge pipe projecting axially through said conical end of the drum in spaced relation to the 30 wall of said material discharge opening for conducting hot gases and products of combustion from the drum, a manually openable closure for said material discharge opening, and a stationary hollow shaft upon which the other end of 35 said drum is journaled, said last-named shaft being adapted for connection with a source of hot gases or products of combustion whereby the latter are introduced into said drum, said closure being threaded on said discharge pipe. 40

3. A rotary kiln of the character described comprising a drum mounted for rotation about a horizontal axis and having a conical end provided with an axial material discharge opening, a pipe projecting axially through said conical end 45 of the drum in spaced relation to the wall of said material discharge opening for conducting hot gases and products of combustion from the drum, a manually openable closure for said material discharge opening, a stationary hollow shaft upon 50 which the other end of said drum is journaled, said last-named shaft being adapted for connection with a source of hot gases or products of combustion whereby the latter are introduced into said drum, means for driving said drum in 55 opposite directions, and spiral scoop-like blades on the interior of said drum for automatically discharging the material from the drum when the latter is rotated in one direction and the closure is opened. 60

4. A rotary kiln of the character described comprising a drum mounted for rotation about a horizontal axis and having a conical end provided with an axial material discharge opening, a pipe projecting axially through said conical end 65 of the drum in spaced relation to the wall of said material discharge opening for conducting hot gases and products of combustion from the drum, a manually openable closure for said material discharge opening, a stationary hollow shaft upon 70 which the other end of said drum is journaled, said last-named shaft being adapted for connection with a source of hot gases or products of combustion whereby the latter are introduced into said drum, and means for manually 75

controlling the discharge of hot gases or products of combustion from said drum.

5. A rotary kiln of the character described comprising a drum mounted for rotation about a horizontal axis and having a conical end provided with an axial material discharge opening, a discharge pipe projecting axially through said conical end of the drum in spaced relation to the wall of said material discharge opening for conducting hot gases and products of combustion from the drum, a manually openable closure for said material discharge opening, a stationary hollow shaft upon which the other end of said drum is journaled, said last-named shaft being adapted 10 for connection with a source of hot gases or products of combustion whereby the latter are introduced into said drum, means for manually controlling the discharge of hot gases or products of combustion from said drum, said last-named 15 means comprising a conduit connected to said discharge pipe, and a shut-off valve in said conduit, 20 means comprising a conduit connected to said discharge pipe, a shut-off valve in said conduit, said discharge pipe and said closure being arranged to rotate with the drum, and a swivel connection between said conduit and said discharge pipe.

6. A rotary kiln of the character described com-

prising a drum mounted for rotation about a horizontal axis and having a conical end provided with an axial material discharge opening, a discharge pipe projecting axially through said conical end of the drum in spaced relation to the wall of said material discharge opening for conducting hot gases and products of combustion from the drum, a manually openable closure for said material discharge opening, a stationary hollow shaft upon which the other end of said drum is journaled, said last-named shaft being adapted for connection with a source of hot gases or products of combustion whereby the latter are introduced into said drum, means for manually controlling the discharge of hot gases or products of combustion from said drum, said last-named means comprising a conduit connected to said discharge pipe, a shut-off valve in said conduit, said discharge pipe and said closure being arranged to rotate with the drum, and a swivel connection between said conduit and said discharge pipe.

GEORGE FREDERICK HORTON.
